(57) **CLAIM**

We claim the ornamental design for a handheld barcode scanner, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a handheld barcode scanner showing our new design from the front, top, and right side; FIG. 2 is another perspective view thereof shown from the front, bottom, and right side;

FIG. 3 is another perspective view thereof shown from the rear, top, and left side;

FIG. 4 is a right side elevation view thereof, the left side elevation view being a mirror image thereof;

FIG. 5 is a front elevation view thereof;

FIG. 6 is a rear elevation view thereof;

FIG. 7 is a top plan view thereof; and,

FIG. 8 is another perspective view thereof shown from the rear, bottom, and left side.

The broken lines are directed to unclaimed features and form no part of the claimed design.
